ADJUSTABLE PATTERN

August Rozek, New York, N. Y.

Application May 7, 1931, Serial No. 535,595

10. Claims. (Cl. 33—15)

In making a garment which will properly fit a person, it has been customary to take certain measurements of the person to be fitted, cut patterns in accordance with these measurements, cut the material in accordance with the patterns, assemble the parts in a readily detachable form, and then make a trial fit of the partly finished garment on the person before it is completed. In making this trial fit, the various sections of the garment must be readjusted to the desired relative positions. This readjustment sometimes makes it necessary to take the sections entirely apart and reassemble them on the person, thereby resulting in a loss of time, and exhausting the patience of the customer.

One object of the present invention is to provide an adjustable garment pattern which is adapted to be conveniently applied to the person to be fitted, and which is provided with means whereby the marginal or peripheral outline may be altered or adjusted at any selective point thereof to conform with the contour of the person being fitted. This pattern may be accurately adjusted so as to permit the cutting of the material therefrom to produce a perfectly proportioned and fitted garment without requiring the taking of measurements or a trial fit of the partly finished garment on the person for which it is intended.

The sections constituting my improved pattern are of a flexible nature, and are provided with means whereby the adjoining sections of the pattern may be detachably connected. One advantageous type of fastening means which may be provided is the so-called "hookless fastener" or zipper which permits the ready attachment or detachment of the various sections of the garment pattern.

The configuration of the marginal or peripheral outlines of the pattern sections along which the garment material is to be cut are controlled by interlaced members in the form of flexible strips or tapes connected to the portions of the patterns adjoining these outlines. These members are arranged to permit adjustment of any desired part of these peripheral portions by the manipulation of these members. By such adjustments, the pattern sections may be altered to conform with the general contour of the person being fitted. The pattern sections may be similarly provided with lacing members for effecting adjustments of such details as the collar or neck, the bust portion and the like, or if desired, the salient points of these details may be deter-

mined by auxiliary pattern sections extensibly connected to the main pattern sections.

In the accompanying drawings, there is shown for the purpose of illustration, one form embodying the present invention, and in which

Fig. 1 is a perspective of the front section of a pattern for a woman's coat as applied to the person to be fitted.

Fig. 2 is a perspective of the back section of the coat pattern of Fig. 1.

Fig. 3 is a plan view of the front left section of the pattern shown in Fig. 1.

Fig. 4 is a plan view of the rear left section of the pattern.

Figs. 5, 6, 7, 8 and 9 are sections taken on lines 5—5, 6—6, 7—7, 8—8, and 9—9 respectively, of Fig. 3.

Fig. 10 shows the upper portion of Fig. 4 in greater detail, and on a larger scale.

Figs. 11 and 12 are sections taken on line 11—11 and 12—12 respectively, of Fig. 10, and

Fig. 13 is a perspective view of details of the lacing shown in Fig. 4, and on a larger scale.

The invention has been illustrated as applied to a coat, but it is understood that it is applicable to any other garment desired.

The main portion of the garment pattern includes a right side front section A, and a left side front section B, and two interconnected rear sections C and D respectively. Suitable means are provided for detachably connecting these pattern sections together. One form of fastening means which may be advantageously used is the so-called zipper or "hookless fasteners". The section A is connected to the section C by means of such a fastening arrangement 10, and the section B is connected to the section D by a similar arrangement 11, the two rear sections C and D being connected together by the zipper fasteners 12. By means of this arrangement, the various pattern sections may be connected to form an assembled pattern or draft garment which is applied to the person to be fitted. This pattern can then be adjusted according to the contours of the person, and thereafter the constituent sections may be separated to permit the cutting of a paper pattern or the garment material directly therefrom.

In order to provide means whereby the width of the pattern sections at any selective point may be varied or adjusted or the configuration of their outlines modified, the portions of the sections to be adjusted having connected thereto lacing members which are slidably secured together by guide strips and loops. These lacing mem-

- bers are arranged so that the sections may be altered at any selective point by manipulation of the corresponding lacing members.
- In Figs. 4, 10 and 13, there is shown a rear section D including two side strips 13 and 14 made of cloth or other suitable flexible material, and extending longitudinally of the pattern section. The outer edges of these strips 13 and 14 constitute the seam edges along which the garment material is to be cut, and are each provided with a series of hookless fastening elements 17 and 18 respectively, by means of which this pattern section D may be connected to the adjoining sections C and B.
- For adjusting the outline of the main portion of the pattern section, the strip 13 has connected thereto a series of spaced transversely extending flexible lacing members 20. The free ends of these lacing members 20 are connected to a longitudinally extending tape 21 which serves to facilitate the grasping of these ends of said members. The strip 14 has similarly associated therewith a series of transversely extending spaced flexible lacing members 22, each having one end stitched or otherwise connected thereto. The other ends are connected together by a longitudinally extending tape or band 23 which serves as a means for grasping these latter ends of the members.
- The strips 13 and 14 have stitched or otherwise connected thereto tapes or bands 24 and 25 which serve as graspable members and which are looped over the lacing members 22 and 20 respectively so as not to interfere with the relative slidable movement of these lacing members. The lacing members 20 and 22 are arranged alternately with the members of one series disposed in the space between successive members of the other series. The lacing members 20 and 22 are advantageously in ribbon form and are sufficiently close together to prevent the forming of large openings or gaps on these pattern sections.
- The two series of lacing members are guided and slidably secured together by suitable guide strips and loops. For this purpose, there is provided a pair of flexible foundation strips 26 and 27 which are similar to and disposed between the strips 13 and 14, and which extend longitudinally with respect to the pattern section. Extending along the strip 26 are four guide tapes or ribbons 28, 29, 30 and 31 stitched or otherwise connected to said strip at intervals so as to provide loops between the stitches under which the lacing members 20 and 22 are guided and interlaced. The loops in the strip 28 are aligned with the loops in the strip 30 and arranged in staggered relation with the loops formed in the tapes 29 and 31. In this way, each lacing member is guided underneath a loop of one guide tape and over the stitched portion of an adjoining tape.
- The strip 27 is also provided with tapes 28', 29', 30' and 31' similar to the tapes 28, 29, 30 and 31, and similarly interlaced with the lacing members 20 and 22 so as to slidably secure said members together.
- In order to guide the lacing members 22 in apposition to the side strip 13 and prevent the flapping of the graspable ends of these members, there is provided a guide strip 32 which is sewed or otherwise connected to said strip 13 at intervals so as to create loops through which these lacing members pass. Similarly, the strip 14 is provided with a guide strip 33 which serves to hold the lacing members 20 in apposition to said strip 14.
- In adjusting the main portion of the pattern section D, when it is desired, for instance, to narrow the width of said section at any selective point, the tape members 21 and 23 are held at points corresponding to the points where adjustment is desired and pulled apart, until the pattern section is narrowed to the necessary extent to conform with the figure being fitted. This operation serves to draw the strips 13 and 14 together and to correspondingly change the configuration of the seam edges thereof.
- When it is desired to widen the pattern section D at any selective point, the corresponding portions of the bands 24 and 25 are pulled apart so as to move the strips 13 and 14 away from each other. When the strips 13 and 14 are spread apart as a result of this operation, the portion of the lacing members 20 and 22 disposed between these strips and the foundation strips 26 and 27 become loose and baggy. In order to obviate this condition, it is desirable to move the strips 26 and 27 so as to decrease the space between these strips and the side strips 13 and 14. For that purpose, each of the strips 26 and 27 has connected thereto holding members in the form of bands 34 and 35, each band 34 being advantageously sewed along one edge thereof to the loops of the tape 28 so that said band 34 may be grasped to move the strips 26 or 27 to the left as shown in Fig. 13. The bands 35 are similarly sewed onto the tapes 31 to facilitate the operation of moving either strip 26 or 27 to the right as viewed in Fig. 13. These two bands 34 and 35 are looped over the lacing members 20 and 22 so as not to interfere with the relative slidable movement of these lacing members. If desired, one such band only may be provided for each foundation strip 26 and 27, and may be used to effect the movement of these strips in either direction.
- In order to maintain the lacing members 20 and 22 in adjusted position, the tapes 28, 29, 30 and 31 are very tautly sewed to or attached to the strips 26 and 27. The tautness of these tapes serves to frictionally hold the lacing members 20 and 22 in adjusted position. In order, however, to further aid in the frictional hold of these lacing members 20 and 22, it is advantageous that these members and the tapes 28, 29, 30 and 31 have a coarse or fluted surface. For that purpose, it is advantageous to use grosgrain ribbon therefor. To further insure the holding of the lacing members 20 and 22 in adjusted position, these members may be pinned on to the foundation strips of the pattern after being adjusted to the desired position.
- To provide means for adjusting the detail portions of the pattern section D, the upper portion thereof is provided with a slit 36, both sides of which are provided with hookless fastening elements cooperating with a slider 36a by means of which said slit may be closed. The purpose of this slit is to permit the portion of the pattern on both sides thereof to lie in a plane when the garment material or pattern is being cut therefrom, irrespective of the curvature of this portion of the pattern section when in fitted position.
- The intermediate shoulder portion of the pattern section D is provided with a lacing arrangement which permits of the adjustment of this portion in accordance with the curvature of the shoulder of the person being fitted. This lacing arrangement serves to alter the distance between the edges of the slit 36 and the right hand edge along the fastening elements 17, and takes the form of a series of lacing members 37, one set of corresponding ends of which are sewed or otherwise connected to the upper portion of the side strip 13, the other corresponding ends of these

5 lacing members being connected together by a tape member 38. Cooperating with this lacing series is another lacing series consisting of a plurality of lacing members 40 disposed in stagger relationship, with the lacing members 37, and having one set of corresponding ends thereof sewed or otherwise connected to the upper portion of the strip 27, the other corresponding ends being connected together by the upper portion 10 of the tape 24. By means of this auxiliary arrangement, the pattern section D may be adjusted to conform with the curvature of the shoulder of the person being fitted.

15 In order to provide for the adjustment of the shoulder strap portion of the pattern section D, the upper portion of the pattern section D to the left of the slit 36 shown in Fig. 10 has sewed thereon a piece of flexible material 45. This material 45 is advantageously sewed to the 20 strip 26 at intervals to provide loops 47. The upper portion of the pattern section D to the right of the slit 36 (Fig. 10) is similarly provided with a piece of flexible material 48 stitched to the upper portion of the strip 27 to provide loops 50. Guided in the loops 47 is a set of spaced 25 straps 51, and guided in the loops 50 is a similar series of spaced straps 52. One set of corresponding ends of these straps 51 and 52 are connected together by means of a tape member 53. The opposite set of ends of the straps 51 are 30 connected together by means of a tape member 54 which extends beyond the aggregate width of these straps, and which is provided with a series of "hookless fastening" elements 55. Slidable along these fastening elements is a slider 56 which serves to connect the upper portion of 35 the pattern section D to the corresponding shoulder strap of the pattern section B hereinafter referred to.

40 The upper ends of the straps 52 are similarly connected together by means of a tape member 57. This tape member 57 is provided with means whereby it may be connected to the tape member 54, this means advantageously taking the 45 form of clasp members 58 cooperating with clasp members 60 on the tape member 54. By means of this arrangement, the straps 51 and 52 may be slid in the loops 47 and 50 in accordance with 50 the desired adjustment of the shoulder strap portion of the pattern. These straps 51 and 52 are advantageously made of the same material as the lacing members 20 and 22.

55 In order to provide means for determining the salient points of the collar or neck measurements, the upper portion of the strip 13 has attached thereto a piece of flexible material 61 which is sewed onto said strip along the sides thereof to provide a passage in which is slidably disposed a tab 62, the upper end of which terminates in a collar or neck section 63. The position of this collar may be adjusted vertically to conform with the neck of the person being fitted, and may then be pinned in adjusted position.

60 The front pattern section B (Figs. 3, 5 and 6) 65 has the main portion thereof provided with a lacing arrangement which is somewhat similar to the lacing arrangement of the main portion of the pattern section D, except that three foundation strips are provided. This pattern section B 70 has two side strips 65 and 66 made of flexible material, and extending longitudinally with respect to the pattern section. The edges of these strips constitute the line along which the garment material is to be cut, the strip 65 being 75 provided with a series of "hookless fastening"

elements 67 by means of which this edge may be attached to the seam edge of the strip 14. For effecting this attachment of the two sections B and D, the fastening elements 67 have slidably, mounted thereof a slider 68.

5 The strip 65 has associated therewith a series of transversely extending flexible lacing members 70 arranged in grid fashion and having one set of corresponding ends thereof stitched or otherwise connected to said strip 65, and joined together by a tape member 70a. The other corresponding ends of these lacing members 70 are connected together by a longitudinally extending tape 71 serving the same purpose as the tape 21 of the pattern section B.

15 The strip 66 has similarly associated therewith a series of transversely extending flexible lacing members 72, one set of corresponding ends of which are stitched or otherwise connected to the strip, and joined together by a tape member 72a, 20 the other set of corresponding ends being connected together by a longitudinally extending tape or band 73 which serves the same function as the tape member 23 associated with the pattern section D.

25 The lacing members 70 and 72 are arranged in staggered relationship similarly to the lacing members 20 and 22, and are made of the same material and slidably secured together by suitable guide strips and loops. For this purpose, there is provided three flexible foundation strips 74, 75 and 76 which are similar to the strips 26 and 27 of the pattern section D, and each of which has extending longitudinally therealong four tapes 77, 78, 79 and 80. These tapes are stitched 30 at intervals to provide loops for interlacing the lacing members 70 and 72 in a way similar to that already discussed with reference to the pattern section D. The lacing members 70 and 72 are guided in apposition to the side strips 65 and 40 66 by means of guide strips 81 and 82, and each of the foundation strips 74, 75 and 76 has connected thereto a pair of holding members 83 and 84 which serve to facilitate the transverse movement of the foundation strips associated therewith. This transverse movement serves to obviate the loose and baggy condition of the lacing members between the foundation strips when the two outside strips 65 and 66 have been spread apart.

45 The upper portion of the pattern section B is provided with means whereby the pattern may be adjusted in accordance with the contour of the bust of the person being fitted. For that purpose, this upper portion of the pattern section B intermediate the sides thereof has a slit 90, both sides 50 of which are provided with "hookless fastening" elements cooperating with a slider 91 by means of which said slit may be closed. This slit permits the portion of the pattern on both sides 55 thereof to lie in a plane when the garment material or pattern is being cut therefrom, irrespective of the curvature of this portion of the pattern section when in fitted position.

60 The bust portion of the pattern section nearest 65 to the arm hole is provided with a lacing arrangement which is similar to the upper lacing arrangement of the pattern section D. This lacing arrangement serves to adjust the bust portion of the pattern section B to the right of the slit 90 70 and takes the form of a series of lacing members 92, one set of corresponding ends of which are sewed or otherwise connected to the upper portion of the side strip 65 and jointed together by a tape member 92a, the other set of corresponding 75

ends being connected together by a tape member 93. Cooperating with this series of lacing members 92 is another series of lacing members 94 disposed in staggered relationship with the lacing members 92, and having one set of corresponding ends thereof sewed or otherwise connected to the upper portion of the strip 76. These lacing members 94 are connected together by a tape member 94a. The other set of corresponding ends 10 of these lacing members 94 are connected together by a tape member 95. These lacing members 92 and 94 are interlaced and slidably connected together by means of bands 96 and 97 secured at intervals to the strips 65 and 76 respectively, so as to provide loops for guiding these interlacing members for slidable movement.

The adjustment of the bust portion of the pattern section B nearest to the arm hole is effected by means of the lacing members 92 and 94 in a manner similar to the adjustment of the shoulder portion of the pattern section D already described.

The bust portion of the pattern section B to the left of the slit 90 is provided with a lacing arrangement which consists of a series of lacing members 100, one set of corresponding ends of which are connected to the foundation strip 75, and joined together by a tape member 101. The other set of corresponding ends of these lacing members 100 are loose and connected together by a tape member 102. Cooperating with this series of lacing members 100 is another series of lacing members 103 disposed in staggered relationship with the lacing members 100, and having one set of corresponding ends thereof connected to the upper portion of the side strip 66, and joined together by a tape member 104. The other set of corresponding ends of these lacing members 103 are loose and connected together by a tape member 105. Both series of lacing members 100 and 103 are disposed in staggered relationship with each other, and slidably connected together by means of the bands 77, 78, 79 and 80 arranged with reference to these lacing members in a manner similar to their arrangement with the lacing members 70 and 72 in the main portion of the pattern section. These series of lacing members are also guided in apposition to the strips 66 and 75 by means of the band 81, and a band 106 sewed to the foundation strip 76. This lacing arrangement serves to effect the adjustment of the bust portion of the pattern section B to the left of the slit 90 in a manner similar to the adjustment of the main portion of the pattern section.

In order to provide for the adjustment of the shoulder strap portion of the pattern section B to conform with the adjustment of the shoulder strap portion of the pattern section D, the upper ends of the strips 65 and 76 have connected thereto a piece of flexible material 107 which is stitched at intervals to provide loops or guide passages 108. Slidably mounted in these guide passages 108 are a series of bands 110, one corresponding ends of which are connected together by a tape member 111, the other set of corresponding ends of which are similarly connected with a tape member 112. These bands 110 may be shifted along the guide passages 108 so as to effect any selective adjustment. The upper edge of the tape member 112 is provided with a series of "hookless fastening" elements 113 adapted to cooperate with the fastening elements 55 of the pattern section D.

The construction of the pattern sections A and C has not been described, but it should be understood that these sections are similar to the sec-

tions B and D respectively. After all the sections have been fastened together in the form of a draft garment and applied to the person to be fitted, the various changeable outlines of the pattern sections are adjusted as already described. The elements of the pattern sections, after being adjusted, may be maintained in position by pinning. The various pattern sections are then separated from each other, and the garment material directly cut therefrom, or, if desired, a paper pattern may be first made therefrom and the garment material cut from said paper pattern.

Having thus described my invention, what I claim as new and desire to secure by Letters Patent is:

1. A pattern section for garments, including a pair of flexible strips, the outer edges of which constitute the outlines which determine the edges of the pattern sections, a first series of lacing members arranged in grid fashion, and each having one end connected to one of said strips for movement therewith, a second series of flexible lacing members arranged in grid fashion, and each having one end connected to the other flexible strip, and means for slidably securing said series of lacing members together whereby the lacing members of each series may be moved relatively to those of the other to move the corresponding edge of the strips.

2. A pattern section, including a pair of flexible side strips, the outer edges of which constitute the outlines which determine the edges of the pattern, a first series of flexible lacing members arranged in grid fashion, and having one set of corresponding ends thereof connected to one of said side strips for movement therewith, a second series of flexible lacing members arranged in grid fashion and connected to the other strip for movement therewith, said second series of lacing members being arranged in staggered relationship, with the lacing members of the other series, and disposed in the space between adjoining lacing members of said last mentioned series, and means for slidably securing said lacing members together whereby the distance between the side strips at any selective point may be adjusted.

3. A pattern section, including a pair of flexible side strips, the outside edges of which constitute the outlines which determine the edges of the garment sections, a first series of flexible lacing members in ribbon form and arranged in grid fashion, said lacing members having one set of corresponding ends thereof connected to one of said side strips for movement therewith, a second series of flexible lacing members arranged in grid fashion and connected to the other strip for movement therewith, said second series of lacing members being arranged in staggered relationship with respect to the lacing members of the other series, and disposed in the space between adjoining lacing members of said last mentioned series, the spaces between adjoining members of one series being substantially as wide as the width of the lacing members of the other series, whereby the creation of large openings or gaps in the pattern section is obviated, and means for slidably securing said lacing members together whereby the distance between the side strips at any selective point may be adjusted, said last mentioned means including a foundation strip disposed intermediate said side strips and extending longitudinally with respect to the pattern section, and a plurality of flexible guide members connected to said foundation strip and extending longitudi- 75

nally therealong, said members forming guide loops arranged in staggered relationship with the loops of adjoining interlacing members and serving to guide said lacing members therethrough.

5. A garment pattern, including a pair of side strips and two series of laces, the laces of one series being secured to one strip, and the laces of the other series being secured to the other strip, the laces of each series being spaced apart and arranged alternately with those of the other series, an intermediate strip, and means on said intermediate strip for guiding said laces for slidable movement.

10. A garment pattern, including a pair of side strips and two series of laces, the laces of one series being secured to one strip, and the laces of the other series being secured to the other strip, the laces of each series being spaced apart and arranged alternately with those of the other series, means for guiding said laces for slidable movement, and tapes connecting together the slidable ends of each series whereby upon pulling said tapes apart at any point the pattern is narrowed at said point.

20. A pattern section including a pair of flexible peripheral side strips extending longitudinally in the lower portion thereof, means including a plurality of closely adjoining, flexible lacing members connected to said strips for adjusting the distance between said strips at any selective horizontal region, the upper portion of said section being provided with a slit open at its upper end and extending longitudinally downwardly, whereby said upper portion of said section may be developed into plane form after being adjusted to substantially conform with the curvature of the person being fitted, and means including two sets of closely adjoining, flexible lacing members on opposite sides of said slit for adjusting the peripheral outlines of the two upper sections formed on opposite sides of said slit.

25. A pattern section for garments, including a strip, the outer edge of which determines one outline of the garment section, a series of flexible lacing members arranged in grid fashion and

each having one end thereof connected to said strip for movement therewith, a foundation strip spaced from said first mentioned strip, and guide loops on said foundation strip for guiding said lacing members for slidable movement with respect to said foundation strip, said loops being sufficiently small to frictionally hold said lacing members in adjusted position, and said lacing members having coarse or fluted surfaces to increase the frictional engagement between said 10 guide loops and said lacing members.

30. A garment pattern having an adjustable main body portion, means for adjusting the peripheral side outlines of said body portion in accordance with the garment fitting measurements of a person, and a shoulder section including a pair of transversely spaced tape members extending laterally of the pattern and connected together by a series of flexible bands arranged in grid fashion and extending lengthwise of the 20 pattern, the upper portion of the pattern being provided with a plurality of adjoining loops for receiving said bands, and for guiding them for slidable movement.

35. A garment pattern having an adjustable main body portion and a shoulder section, including a pair of transversely spaced tape members extending laterally of the pattern and connected together by a series of flexible bands arranged in grid fashion and extending lengthwise of the 30 pattern, and means for guiding said bands for slidable movement lengthwise of said pattern.

40. A garment pattern having an adjustable main body portion and a shoulder section, including a piece of flexible material, a pair of transversely spaced tape members extending laterally of the pattern respectively above and below the ends of said piece of flexible material and connected together by a series of flexible bands arranged in grid fashion, and extending lengthwise 40 of the pattern adjacent to the inner side of said piece of flexible material, and means for guiding said flexible bands for slidable movement lengthwise of the pattern.

AUGUST ROZEK. 45
